UNITED STATES PATENT OFFICE.

JAMES C. MEEM, OF BROOKLYN, NEW YORK, ASSIGNOR OF ONE-THIRD TO FREDERICK L. CRANFORD AND ONE-THIRD TO WALTER V. CRANFORD, OF BROOKLYN, NEW YORK.

METHOD OF CONSTRUCTION.

No. 884,990.

Specification of Letters Patent.

Patented April 14, 1908.

Application filed September 6, 1907. Serial No. 391,577.

To all whom it may concern:

Be it known that I, JAMES C. MEEM, a citizen of the United States, residing at the borough of Brooklyn, in the county of Kings and State of New York, have invented certain new and useful Improvements in Methods of Construction, of which the following is a full, clear, and exact description.

This invention relates to a method of partially submerged construction, and more particularly has reference to a method whereby foundations, tunnels, or other structures, or portions of structures, partly above and partly below the water, may be safely constructed.

In carrying out the method of the invention, a preliminary excavation is made down to the water level and preferably is somewhat larger than the tunnel or foundation to be constructed. Within this excavation, sheeting or piling forming a fixed caisson, is set up and driven to a level below the water level, leaving a stationary portion thereof extending above the water level. This stationary portion is air proofed and weighted so as to form a caisson where necessary, and provided with the usual air locks and other apparatus. Having erected this caisson, it is now possible to excavate from the interior, under air pressure where necessary, to hold back the water, in the usual manner. In going to a greater depth than the sheeting first driven, additional sheeting and bracing are driven on the forward end in such manner as not to restrict the clear space, so that the interior of the caisson has a certain minimum area and is protected from caving in. In this manner it is possible to extend the caisson as the excavation proceeds, leaving the top at all times fixed, and with such method, excavations can be made through non-homogeneous soils where ordinary caissons could not be driven by reason of obstructions preventing their movement.

The invention will be more fully understood in connection with the accompanying drawings, in which

Figure 1 is a sectional view showing a tunnel or foundation in course of construction, wherein the excavation is made down to the water level and the stationary caisson and air locks are in place ready for the interior excavation.

Referring to the figure, A represents the ground in which the tunnel or foundation is

to be commenced or built, and B represents the water level therein, either the normal water level or a temporarily lowered water level produced by pumping.

C represents an excavation made down to the water level B, and shored up or braced by sheet piling D and cross braces E. Within this excavation C are driven sheet piles F closely together, around the space to be excavated under the water level B, and these piles F are braced by horizontal braces G, in the usual manner. The top of the piles F is leveled off and provided with a waling H, and secured to the piles and the waling is a roof I, provided with one or more shafts J 70 having the usual air locks and air pipes therein. The roof I is made to be stationary and for this purpose may be loaded with timbers or concrete K to resist the upward reaction of the air pressure and may be braced within 75 the piles F by braces L. The piles F having been driven, the roof put on, and the space above the water level B air proofed in the usual manner, the interior of the caisson can now be excavated, under air if necessary, or 80 the water kept back by pumping. As the excavation goes onward, the sides of the caisson will be braced, and when the excavation has reached the bottoms of the piles, in case it is desired to go further, additional piles or 85 sides M will be added as the excavation proceeds. These additional sides or extensions M are made of somewhat shorter sections of sheet piling driven downwardly and outwardly at an incline, and having the joints 90 closed, as by concrete N, and suitably braced, so that the whole forms a rigid structure. In doing this, the water and the ground, such as quick sand or mud, may be held back by the air pressure. When the excavation has proceeded in this manner as far 95 downward as is desired, it will be filled up, in the case of a foundation, or lined, as in the case of a tunnel or subway.

It will be seen that by this method, it is unnecessary to move the whole caisson as the work progresses, which is an expensive and objectionable process. In forcing built-up caissons as the excavation proceeds, and especially in soils containing boulders, the progress of the whole caisson may be stopped by a boulder, whereas by this method of driving piles, only those piles which strike the boulder will be stopped and the others can be driven as far as is desirable. After the 110

interior has been excavated to the rock, it can be broken up and removed, or a new set of piles can be driven onward from around the rock. In this manner, excavations can be 5 made under water by means of caissons which are built in the direction of the excavation as it proceeds, the water and soil being held back by air pressure where necessary.

The general characteristic of this method, 10 resides in the manner of building a partially submerged structure by means of a caisson or section built as the interior excavation proceeds, the roof being built and fixed once for all. The expense of building a tunnel or 15 sub-aqueous structure is thus very greatly reduced, and this method will also be of advantage in situations where the overhead space for the erection of an ordinary caisson is limited.

20 A further advantage of the method resides in the caisson itself, which is built up of sections driven longitudinally of the excavation to the extent desired, so that the progress of the caisson as a whole is not hindered by obstructions at portions thereof. By driving 25 the piling forming the forward sections in an outwardly inclined direction, an indefinite number of sections can be added on without decreasing the interior area of the caisson, 30 and this is an important consideration, as much unnecessary excavation is thereby saved.

It will further be observed that the roof is at all times above the water level, while the 35 actual excavation is below.

It will be understood that the specific construction of caisson and the manner of building up the same, herein described, is for purposes of illustration only, and that the 40 method can be carried out by other arrangements without departing from the scope of the invention.

It will also be understood that I do not restrict myself to any particular location of the 45 air locks, which are shown herein in the fixed roof, as these may be located in the side walls, or elsewhere if desired, without affecting or departing from the scope of the invention.

50 Having thus described my invention, I de-

clare that what I claim as new and desire to secure by Letters Patent, is:—

1. A method of building a pneumatic caisson for excavation, which consists in driving side walls from above below the level of the 55 water, building a fixed roof thereon, and extending the sides from the forward end as the excavation proceeds.

2. A method of building a pneumatic caisson consisting in building a fixed air proof 60 top section extending from below the water level upward, and extending the caisson from the water level downward by inclined sections in advance of the excavation.

3. A method of making a sub-aqueous 65 excavation which consists in building a fixed air proof caisson extending from below the water level upwards, preventing rise of water within the caisson, and extending the caisson forwardly by additional sections in the direction of and in advance of the excavation.

4. A method of building a pneumatic caisson consisting in forming a caisson of driven sheeting or piling to a penetration below the level of the water, attaching a fixed roof 75 thereto above the water level, providing a shaft therein, and sheeting at the forward end in advance of the excavation.

5. A method of building a pneumatic caisson consisting in forming a caisson of driven 80 sheeting or piling to a penetration below the level of the water, attaching a fixed roof thereto above the water level, providing a shaft for the caisson, sheeting at the forward end in advance of the excavation, and applying air 85 pressure.

6. A caisson composed of a stationary top, and inclined sections built on at the bottom as the excavation proceeds.

7. A caisson composed of a stationary top 90 fixed to withstand air pressure, and sections built on at the bottom as the excavation proceeds, and sealed at the junctions.

In testimony whereof I affix my signature, in presence of two witnesses.

JAMES C. MEEM.
